UNITED STATES PATENT OFFICE.

ANTHONY ZIMMIEWICZ, OF NEW YORK, N. Y., ASSIGNEE, BY MESME ASSIGNMENTS, TO
MINNIE PRINTING PRESS & MANUFACTURING COMPANY, OF CHICAGO, ILLINOIS,
A CORPORATION OF ILLINOIS.

PAPER-CUTTING MECHANISM.

Application filed December 15, 1924. Serial No. 756,114.

My present invention relates generally to paper cutting apparatus and more particularly to a paper cutting mechanism utilized in connection with newspaper printing presses, along with mechanism adapting the cut sheets to be collected and stacked at full press speed. More especially my present invention forms a part of an associating and delivering mechanism included in an application filed of even date herewith.

Among the objects of my present invention, the most important is the provision of a cutting mechanism which is readily adjustable and will efficiently operate to cut a moving web along lines at right angles to its side edges irrespective of the particular speed of the moving web.

With these and other objects in mind my invention will be more plainly understood by reference to the accompanying drawings which illustrate the invention and form a part of this specification, and in which:

Figure 1 is a diagrammatic view in section showing the cutting mechanism with the adjacent web feeding parts and guides for the cut sheets.

Figure 2 is an enlarged section through the cutting mechanism alone.

Figure 3 is a top plan view thereof,

Figure 4 is a detail side view of the cutter cylinder removed, and

Figure 5 is a similar view of the cutter bar with its stationary blade.

Referring now to these figures and particularly to Figure 1, there is shown a printer web 10 fed, as in practice, through pairs of pulling through rollers 11 to and across the knife bar 12 of the web cutting mechanism which forms the subject matter of the present application and which is also included in an application for associating and delivery apparatus filed of even date herewith, Serial No. 756,115.

I have also shown in Figure 1 portions 45 13 of a newspaper printing press from which the printer web 10 in practice proceeds, those portions illustrated being sufficient to show the connection of the driving shaft 14 of the cutting mechanism with the printing mechanism.

The knife bar 12 is a rigid part of the knife carriage 15 whose sides are adjustably mounted on the sides of a supporting frame 16. The carriage 15 has at one side

a lower extension 17 through which the upper portion of a vertical shaft 18 is journaled, said shaft forming a pivot upon which the entire knife carriage is horizontally swingable to a more or less inclined angle with respect to the line of the moving web 10. For such horizontally swingable adjustment, the knife carriage has at its opposite sides arcuate openings 19 through which guide pins 20 upstand from the sides of the supporting frame 16, the openings 65 60 65 having a common center concentric with the shaft 18. On the sides of the supporting frame 16, adjusting screws 21 provide for ready quick adjustment of the knife carriage which becomes necessary whenever for 70 any reason the speed of movement of the web 10 is changed.

The shaft 18 is connected at its lower end by bevel gears 22 with the drive shaft 14 extending from the printing press, and 75 is connected at its upper end by bevel gears 23 with a cross shaft 24, the latter having spur gears 25 in engagement with similar, though larger gears 26 on the main cutter shaft 27 in the carriage 15. Upon this 80 main shaft the cutter cylinder 28 is secured, having a knife bar 29 to which a blade 30 is attached, and also having in its length a plurality of discs 31 whose function is to engage the web moving across the knife bar 85 12 and guide and hold the web down so that when severed, the sheets will fall upon conveyor tapes 32 by which the severed sheets are carried away from the cutting mechanism.

It will be observed that in action the blade 30 of the rotating knife bar 29 operates downwardly against the blade 33 of the stationary knife bar 12 and it will also be observed that, upstanding as it does, the 90 stationary knife blade 33 presents its thin edge to the moving blade and being adjustably connected to the knife bar 12 as by means of clamping screws and the like 34, this blade may be readily and effectively adjusted to insure clean uniform cutting of the web whereby to avoid frequent sharpening and shut downs for this purpose.

It will also be noted that, between the printing press 13 and the cutting mechanism, the feed of the paper web to such mechanism is controlled by a compensating roller 35 which is adjustable toward and

away from the cutting mechanism and which thus controls the points of cutting of the web in the cutting mechanism so that the latter will accurately act between the printer sections.

I claim:

1. In a mechanism of the character described, a moving web severing device including rotary and stationary knives, a supporting frame, a frame carrying said knives and adjustable angularly on said supporting frame with respect to the line of movement of the web, rollers for feeding a web into said knife frame, and a roller around which the web extends, said latter roller being adjustable toward and away from the knife frame for the purpose described.
2. In a mechanism of the character described having a supporting frame, a moving web cutting device including stationary and rotary knives, a cutter frame extending across said first named frame and through which the web passes between said knives, connections supporting said cutter frame on said first named frame permitting adjustment of the former angularly with respect to the line of movement of the web, and means for feeding a web to the cutter frame, including means to control the point of cutting of the web, as described.
3. In a mechanism of the character described having a frame, a moving web cutting device including stationary and rotary knives, a cutter frame extending across said first named frame and through which the web passes between said knives, and connections supporting said cutter frame on said first named frame permitting adjustment of the former angularly with respect to the line of movement of the web, said cutter frame having an extension at one side, and a shaft journaled vertically through said extension forming the pivot of adjusting movement of the cutter frame and operatively connected to the rotary knife as described.
4. In a mechanism of the character described having a supporting frame and a drive shaft in said frame, a device for cutting a moving web including a frame through which the web passes, adjustably disposed across the supporting frame and having an extension at one side, a vertical shaft geared to said drive shaft and journaled through said extension and forming the pivot of adjusting movement of the cutter frame, and rotary and stationary cutters mounted in the cutter frame of which the former is operatively connected to the said vertical pivot shaft.
5. In mechanism of the character described, a cutting mechanism for a moving web, a supporting frame in which the web moves, a frame for the cutting mechanism

adjustable on the supporting frame angularly with respect to the moving web, said cutting mechanism including a stationary cutter bar over which the web passes, a cutting cylinder having a cutting blade, and a blade adjustably connected in upright position in said stationary bar with its thin edge toward the cutting cylinder for co-operation with the blade thereof.

6. In a mechanism of the character described having a supporting frame and a drive shaft in said frame, a device for cutting a moving web including a frame through which the web passes, adjustably disposed across the supporting frame and having an extension at one side, a vertical shaft geared to said drive shaft and journaled through said extension and forming the pivot of adjusting movement of the cutter frame, and rotary and stationary cutters mounted in the cutter frame of which the former is operatively connected to the said vertical shaft, said rotary cutter including a cylinder in the cutter frame, and a plurality of spaced apart web-engaging guide discs in said cylinder, as described.

7. In a mechanism of the character described, a moving web severing device including rotary and stationary knives, a supporting frame, a frame carrying said knives and adjustable angularly on said supporting frame with respect to the line of movement to the web, and rollers for feeding a web into said knife frame.

8. In a mechanism of the character described, a moving web severing device including movable and stationary knives, a supporting frame, a frame carrying said knives and adjustable angularly on said supporting frame with respect to the line of movement of the web, rollers for feeding a web into said knife frame, and a roller around which the web extends, said latter roller being adjustable toward and away from the knife frame for the purpose described.

9. In a mechanism of the character described having a supporting frame and a drive shaft in said frame, a device for cutting a moving web including a frame through which the web passes, adjustably disposed across the supporting frame and having an extension at one side, a vertical shaft geared to said drive shaft and journaled through said extension and forming the pivot of adjusting movement of the cutter frame, and rotary and stationary cutters mounted in the cutter frame of which the former is operatively connected to the said vertical pivot shaft.

In testimony whereof I have affixed my signature.

ANTHONY ZIMNIEWICZ.
